(57) **CLAIM**

The ornamental design for a support pillow, as shown and described.

DESCRIPTION

FIG. 1 is a top, front and right side perspective view of a support pillow showing our new design;

FIG. 2 is a top plan view thereof;

FIG. 3 is a front elevation view thereof;

FIG. 4 is a bottom plan view thereof;

FIG. 5 is a rear elevation view thereof;

FIG. 6 is a left side elevation view thereof; and,

FIG. 7 is a right side elevation view thereof.

The broken line showing a reading lamp positioned in the pillow pocket in FIG. 1 is for illustrative environmental purposes and forms no part of the claimed design.
